ATTORNEY

UNITED STATES PATENT OFFICE.

GENEVIEVE PFEFFER, OF SAN JOSE, CALIFORNIA.

DESIGN FOR A DOLL.

53,154.

Specification for Design.

Patented Apr. 1, 1919.

Application filed December 23, 1918. Serial No. 268,104. Term of patent 7 years.

To all whom it may concern:

Be it known that I, GENEVIEVE PFEFFER, a citizen of the United States, residing at San Jose, in the county of Santa Clara and State of California, have invented a new, original, and ornamental Design for Dolls, of which the following is a specification, reference being had to the accompanying drawing, forming part thereof.

The figure is a perspective view of the doll.

I claim:

The ornamental design for a doll, as shown.

GENEVIEVE PFEFFER.

Witnesses:

GEO. J. PFEIFFER,

ANDREW BRAUNINGER.
